UNITED STATES PATENT OFFICE.

WILLIAM F. DERWIN, OF WATERBURY, CONNECTICUT.

PUZZLE.

SPECIFICATION forming part of Letters Patent No. 593,766, dated November 16, 1897.

Application filed March 31, 1897. Serial No. 630,106. (No model.)

To all whom it may concern:

Be it known that I, WILLIAM F. DERWIN, a citizen of the United States, and a resident of Waterbury, in the county of New Haven 5 and State of Connecticut, have invented certain new and useful Improvements in Puzzles, of which the following is a specification.

My invention relates to puzzles or games, and more especially to that class commonly 10 played with marbles or balls and which are produced from wood, cardboard, or sheet metal.

It is the object of my invention to produce a game which will afford recreation and 15 amusement to both young and old and the manipulation of which requires skill and perseverance for its successful operation.

Upon the accompanying drawings, which form a part of this specification, the same 20 letters of reference denote like or corresponding parts upon both figures, and of which—

Figure 1 shows a plan view of my novel puzzle complete; Fig. 2, a cross-section taken on line $\alpha\alpha$ of Fig. 1.

25 In the accompanying drawings, A represents the main floor, which in practice is smooth and level; B B, alleys extending along each side of the main floor and across the front end thereof. Said alleys, as shown 30 upon the drawings, are upon an incline, the same starting at each side from the level of the main floor, as at C C, and gradually sloping to the center of the front end, as at D. Said alleys are provided upon their outer side 35 with a wall E, as shown, which also extends across the rear end and which is a trifle taller than the intermediate partitions upon the main floor of the puzzle.

The main floor of the puzzle is divided by 40 a series of partitions into several compartments, all of which are provided with exits into the alley-ways, the purpose of which will later be more fully explained. The puzzle can be played with any desired number of 45 marbles. In practice, however, I find that five is the most desirable number to use, and consequently I have shown that number in the drawings.

50 Adjacent to the rear end of the puzzle and upon a level with the main floor is a pen F, in which the marbles G are placed just prior to manipulating said puzzle, the first move-

ment of which is to raise the rear end thereof. This pen is provided with an exit, immediately in front of which is situated a deflector 55 H, which serves to separate the several marbles as they emerge from said starting-pen. At either side of said deflector is a passage-way I, leading into the compartment J, and which is provided with exits K at each side 60 thereof leading into the alleys whose floor is slightly below that of the main compartment. The first compartment J is provided with a central passage L, leading into a second compartment M, which is similar in construction and purpose to the first compartment J, above mentioned. This second compartment is in turn provided with side exits N N similar to K K, above mentioned. Said compartment is further provided with passages O O, leading into a third compartment P, which is substantially like the second compartment M, being also provided with side alley-exits Q Q and passage-ways R R, the latter leading into the fourth compartment 75 S, which contains a receiving-cage T, adjacent to the wall E of the forward portion end.

The object to be accomplished in the game is to roll the balls from the starting-pen F through the several compartments J, M, P, 80 and S and passages I, L, O, and R and finally get said balls all in the cage T. The principal difficulty necessary to overcome in accomplishing the above is to prevent the marbles from escaping into the alleys B B at 85 each side of said compartments, the floor of which, as before stated, is above that of said alleys, the latter being upon an incline, which would cause said marbles to roll to the front or lowest point, as at D. Should the latter 90 trouble arise, it will be obvious that said marbles will have to be returned to the rear end and again passed through passages I I of the first compartment.

In this my invention I desire to reserve the 95 right to vary the details of construction in several particulars—namely, that of the alleys, the lower corners of which may be made either rounding or octagon, and also in the matter of the number of compartments, it 100 being obvious that a greater or less number than that shown can be used to the same end or purpose.

Having thus described my invention, what

I claim, and desire to secure by Letters Patent, is—

1. The herein-described puzzle, comprising a main-floor pen F, adjacent to the rear end thereof, compartments J, M and S having exits and passages as shown, cage T upon the front end and marbles G all arranged for the purpose set forth.
2. The herein-described puzzle, comprising a main floor having pen F, compartments, J, M, P and S, side exits leading from said compartments, passage-ways between said compartments, cage T, alley-ways upon each side of the main floor and across the front end thereof.
3. A puzzle substantially as herein shown

and described the same consisting of a main floor and inclined alley-ways upon three sides thereof, a series of compartments upon said main floor, each provided with passage-ways 20 from one to the other and side exits leading into the alley-way, pen F, adjacent to the rear end and cage T at the opposite end, the whole arranged for the purpose specified.

Signed at Waterbury, in the county of New 25 Haven and State of Connecticut, this 24th day of March, A. D. 1897.

WILLIAM F. DERWIN.
